HOWARD M. BARBER, OF WESTERLY, RHODE ISLAND, ASSIGNOR TO C. B. COTTRELL & SONS COMPANY, OF WESTERLY, RHODE ISLAND, A CORPORATION OF DELAWARE.

DRIVING MECHANISM FOR PRINTING PRESSES.

Application filed February 20, 1926. Serial No. 89,686.

In web perfecting rotary printing presses and especially in multi-color printing presses it has been usual to connect the impression cylinder of one of the printing units to the main drive on the outside of the frame and said impression cylinder to its plate cylinders and to the impression and plate cylinders of the other printing cylinder also on the outside of the frame. These connections necessarily cause considerable undesirable vibration of the parts and loss of rigidity, especially as the press is being started, when the starting torque is very high.

The object of my invention is to overcome this vibration and lack of rigidity by providing a primary drive located outside of the frame and a secondary drive located inside of the frame. In the present instance the primary drive is located just outside the train of gears which connect the impression and plate cylinders of the first and second printing units and the secondary drive is placed just inside of the frame and includes a gear fast on the impression cylinder of the second printing unit.

A practical embodiment of my invention is represented in the accompanying drawings, in which

Fig. 1 represents in detail side elevation so much of a multi-color web perfecting rotary printing press as will illustrate my improved driving mechanism therefor.

Fig. 2 represents a detail vertical transverse section taken in the plane of the line II—II of Fig. 1, looking in the direction of the arrows.

The printing press frame is denoted by 1, within which frame are suitably mounted the first and second printing units of a multi-color perfecting rotary printing press.

The impression cylinder of the first printing unit is denoted by 2 and its shaft 3 has fast thereon a gear 4, located outside of the frame 1. This gear 4 meshes with the gears 5 and 6 which are fast on the shafts 7 and 8 of the plate cylinders 9 and 10 of the first printing unit. This gear 4 is driven through the gears 11 and 12 from the gear 13 which is fast on the shaft 14 of the impression cylinder 15 of the second printing unit.

These gears 5, 6, 11, 12 and 13 are all located just outside of the frame 1. The gear 13 meshes with the gears 16, 17, 18 and

19 fast on the shafts 20, 21, 22 and 23 of the plate cylinders 24, 25, 26, and 27 of the second printing unit.

The driving mechanism for the printing press comprises a primary drive and a secondary drive. The primary drive comprises the driving gear 28 and its driven gear 29 which are fast on the shafts 30 and 31 respectively, and located outside of the frame 1 and just outside of the train of gears which connect the primary and secondary printing units.

The secondary drive of the driving mechanism comprises the driving gear 32 and its driven gear 33 which are fast on the shaft 31 and impression cylinder 15 respectively. These gears of the secondary drive are located just inside of the frame 1.

An auxiliary side frame 34 serves as the outside mounting for the shafts 30 and 31.

The shaft 30 may be driven from any suitable source of power, not shown herein, through the longitudinal shaft 35 and bevelled gears 36 and 37 which are fast on the shafts 35 and 30 respectively.

By locating the secondary drive of the driving mechanism just inside of the frame, I find that rigidity is assured even when the parts are subjected to the very high torque at the starting of the press, a feature which is, of course, of very great importance in this type of machinery.

It is evident that various changes may be resorted to in the construction, form and arrangement of the several parts without departing from the spirit and scope of my invention; hence, I do not intend to be limited to the particular embodiment herein shown and described, but

What I claim is:—

1. In a web perfecting rotary printing press, a suitable frame, two printing units, a geared connection between the two units located outside of the frame, and a press driving mechanism comprising a primary drive located outside of the frame and a secondary drive located inside of the frame and including a driven gear fast on the impression cylinder of one of the said printing units.

2. In a web perfecting rotary printing press, a suitable frame, two printing units, a geared connection between the two units located outside of the frame, and a press

driving mechanism comprising primary and secondary drives, the primary drive including driving and driven gears located outside of the frame and the secondary drive including driving and driven gears located inside of the frame.

3. In a web perfecting rotary printing press, a suitable frame, two printing units, a geared connection between the two units located outside of the frame, and a press driving mechanism comprising primary and secondary drives, the primary drive including driving and driven gears located outside of the frame and the secondary drive including driving and driven gears located inside of the frame, the driven gear of the secondary drive being fast on the impression cylinder of one of the printing units.

4. In a web perfecting rotary printing press, a suitable frame, two printing units, a geared connection between the two units located outside of the frame, a press driving mechanism comprising primary and secondary drives, the primary drive including driving and driven gears located outside of the frame and the secondary drive including driving and driven gears located inside of the frame, and a shaft passing through the frame having fast thereon the driven gear of the primary drive and the driving gear of the secondary drive.

5. In a web perfecting rotary printing press, a suitable frame, two printing units,

a geared connection between the two units located outside of the frame, a press driving mechanism comprising primary and secondary drives, the primary drive including driving and driven gears located inside of the frame, and a shaft passing through the frame having fast thereon the driven gear of the primary drive and the driving gear of the secondary drive, the driven gear of the secondary drive being fast on the impression cylinder of one of the printing units.

6. In a web perfecting rotary printing press, a suitable frame, two printing units, a geared connection between the two units located outside of the frame, and a press driving mechanism comprising primary and secondary drives, the primary drive including driving and driven gears located outside of the frame and just outside of the gear connection between the two printing units and the secondary drive including driving and driven gears located just inside of the frame, the driven gear of the secondary drive being fast on the impression cylinder of one of the printing units.

In testimony that I claim the foregoing as my invention, I have signed my name this 18th day of February, 1926.

HOWARD M. BARBER.
